BED SHEET

Annette Fridolph, New York, N. Y.

Application September 19, 1936, Serial No. 101,534

3 Claims. (Cl. 139—391)

This invention relates to a process of forming sheeting for bed sheets and the like and product thereof, and has to do particularly with the forming of bed sheets and similar articles of materially varying surface characteristics.

In the normal weaving of sheeting for use as bed sheets and similar articles, it has been customary to so weave the threads as to form a surface as a smooth hard surface. It is common knowledge that bed sheets so woven give a relatively cold feel in the winter-time with the result that many people use special coverings or warming pads and the like for the feet, or dispense with sheets altogether.

It is the object of the present invention to so weave sheeting, particularly for use as bed sheets, that a portion of the sheeting will present a relatively soft, warm surface; the forming of this soft, warm surface is preferably accomplished as the continuous sheeting leaves the loom, spaced portions of the continuous sheeting being subjected to combing or teasing rolls or the like whereby to give spaced portions of the continuous sheeting a brushed up or flannel-like surface.

The combing rolls may be replaced by the forming of the woof threads or both the woof and the warp threads of relatively soft thread material; in any case, the result being a woven textile fabric or continuous form but having portions of its surface of distinctly different characteristics.

In the drawing:

Fig. 1 is a plan view, largely diagrammatic, of a continuous length of woven sheeting, portions of the surface being processed according to the present method and other portions retaining the relatively hard finished surface.

Fig. 2 is a side elevation similar to Fig. 1, and also largely diagrammatic, illustrating one manner of roughing or combing spaced portions of the continuously woven sheeting.

Fig. 3 is an enlarged fragmentary view of a bed sheet or similar article, the bottom part of the bed sheet for covering the feet being shown at the right of the dash and dot line and the central and upper part of the bed sheet being shown at the left of the dash and dot line.

Fig. 4 is a view similar to Fig. 3 and illustrating the forming of the bottom part of the sheet of warp and woof threads of a different type than those used to form the main part of the sheet.

Figs. 5 and 6 are enlarged fragmentary views similar to Figs. 3 and 4 but illustrating the woof threads alone being formed of softer material.

An essential feature of the present invention

is the fabricating of spaced portions of a length of sheeting, preferably continuous sheeting, whereby to form a relatively soft surface at said spaced fabricated portions. Specifically, the process is particularly applicable to bed sheets and the forming of the fabricated portion for, roughly, thirty inches, and the hard finished smooth portion for the rest of the length, or in some cases it may form substantially half the length of the sheet.

In Fig. 1 I have shown a continuous length of sheeting with a fabricated or processed portion as at 2 and a hard finished standard unprocessed portion as at 3. The continuous sheet may be cut off as desired and the spaced portion 2 obviously may be of any length desired.

In Fig. 2 I have illustrated one method of fabricating and processing the spaced portions in a continuous length of sheeting wherein the sheeting is fed from a loom through brushing or 20 combing rolls 4 which comb out and soften the hard finished surface of the sheeting to give a sort of flannel effect. It is obvious that the rolls may be moved relative to each other in timed relation so as to process a definite length of material at the points desired. In Fig. 3 I have illustrated an enlarged fragmentary plan view of a portion of the continuous sheeting shown in Figs. 1 and 2 and taken at the dividing point between the processed and unprocessed surfaces. 30

In Fig. 4 I have illustrated a modification in that instead of using roughing or combing rolls 4, a softer thread or yarn is tied to the warp and woof threads 5 and 6; in other words, the warp and woof threads coming from the spools are cut 35 and the softer, preferably heavier, yarn is tied on and fed through the loom in the regular way. When the desired length of the continuous sheeting has been woven with the softer yarns, they may be again cut and the standard warp and woof 40 threads again tied on and fed through the loom.

In Fig. 5 I have demonstrated a still further modification in that the warp threads 5 are fed through the loom in the standard way but at certain intervals I prefer to feed through relatively soft and heavy yarns 7 to take the place of the woof threads 6. The feeding of the cross yarns 7 may terminate at any point desired and such section may also be submitted to the roughing or combing rolls 4.

In Fig. 6 I have illustrated a fragmentary enlargement, somewhat similar to Fig. 5, in that relatively heavy woolen yarns 7 are fed crosswise as the woof threads in fabricating the continuous sheeting.

50

55

While the present process is particularly applicable to the fabricating of bed sheets and the like, it will be understood that it may have other uses such as the fabricating of babies' diapers 5 and similar articles requiring both a relatively smooth "cold" surface and a portion having a relatively soft "warm" surface.

What I claim is:

1. As a new article of manufacture, a bed sheet 10 of woven material having the warp and woof threads of a portion thereof of standard formation to present a relatively smooth cold feel, and the warp and woof threads of a widthwise portion adjacent one end of said woven sheet having an 15 exposed surface napped to form a relatively soft surface.

2. As a new article of manufacture, a bed sheet formed of woven material having the warp and woof threads of a portion thereof of standard unnaped formation to present a relatively smooth cold feel on both sides of the sheet, and the warp and woof threads of a widthwise portion adjacent one end of said woven sheet having an exposed surface on opposite sides of the sheet roughed-up to form a relatively soft nap. 5

3. As a new article of manufacture, a bed sheet 10 formed of one piece of woven material having an area thereof extending widthwise of the sheet adjacent one end napped to provide better insulation characteristics, the remainder of the sheet being of standard formation and unnaped. 15
